UNITED STATES PATENT OFFICE.

JOHN J. McGUCKIN, OF BROOKLYN, NEW YORK, ASSIGNOR TO LOUIS SCHWAB, OF NEW YORK, N. Y., DOING BUSINESS AS STEVENS & COMPANY.

VALVE-STEM LENGTHENER.

Application filed May 6, 1922. Serial No. 559,031.

To all whom it may concern:

Be it known that I, JOHN J. McGUCKIN, a citizen of the United States, residing at Brooklyn, Kings County, New York, have 5 invented certain new and useful Improvements in Valve-Stem Lengtheners, of which the following is a specification.

My invention relates to means for stretching and thereby lengthening the valve stems 10 of internal combustion engines, which valve stems have, for instance, become shortened by wear so as not to cooperate properly with the actuating cams; and my improvements are directed particularly to means whereby 15 the stem may be swaged at one or more points so as to stretch the stem lengthways to the desired extent and without bending or distorting the stem from its proper alignment.

20 In the drawings Fig. 1 is a longitudinal sectional view of my improved tool showing a valve stem in place therein; and Fig. 2 is an end view of the same looking to the left on Fig. 1.

25 Similar parts are designated by similar reference numerals in all the figures.

The body 1 of the tool has a central longitudinal bore 2 adapted to receive a valve stem 3 so as to bring it directly between the 30 swaging pistons 4—5, which slide in bores 6 and 7 in hubs 8 and 9 formed integral with the body 1. The pistons are, preferably, prevented from rotating in their sockets by suitable means, such, for instance, as pins 10, 35 11 projecting from the pistons and traveling in slots 12, 13 in the hubs 8 and 9 respectively. The piston 5 is preferably provided with a flange 14 and with a base 15 by which it may be held in suitable supporting means, such as a vise, the jaws of which are indicated by 16, 17 in Fig. 1.

In one end of the body 1 is mounted a gage screw 20, which is threaded through one end of the body 1, and which may be 45 screwed out or in to the body as desired, the gage screw being provided with a suitable milled head 21 by which it may be conveniently turned.

Between the head 21 and the body 1 I 50 prefer to insert, around the gage screw 20, a coiled spring 22 which offers resistance to the turning of the head so as to prevent its jarring out of position during the use of the tool.

55 In practice the correct length of the valve

stem is first ascertained by the use of a thickness gage or the like, and the gage screw 20 is set to mark that length. And the valve stem to be lengthened is inserted in the gage and swaged or stretched lengthways between the pistons 4 and 5, by striking piston 4 with a hammer, so as to drive it down toward 5. If the swaging is done without adjusting the stem lengthwise, a groove or indentation will be formed around 60 the stem, if it is turned slightly between the blows on the piston 4, such a groove being shown in Fig. 1.

The piston may be stretched at more than one point, by varying the distance to which 70 it is inserted in the bore of the body. When the stem has been stretched to the desired extent its end will meet the end of the gage screw 20, when the head of the stem is against the opposite end of the body 1. The 75 opening 30 through the body 1 permits the relation of the valve stem and gage screw to be observed.

It will be understood that details of construction may be modified, by the use of 80 mechanical equivalents and the like, without departing from the spirit of my invention as claimed.

Having thus described my invention, what I claim and desire to secure by Letters Pat- 85 ent of the United States is:—

1. In a valve stem lengthener, the combination of an anvil, a body carried reciprocably thereby and provided with a valve stem supporting portion, and a cooperating 90 hammer element.

2. In a valve stem lengthener, the combination of an anvil, a body carried reciprocably thereby and provided with a laterally extended valve stem supporting portion, and 95 a cooperating hammer element.

3. In a valve stem lengthener, the combination of an anvil, a body carried reciprocably thereby and provided with a valve stem supporting portion and with means for 100 limiting reciprocation in both directions, and a cooperating hammer element.

4. In a valve stem lengthener, the combination of an anvil, a body carried reciprocably thereby and provided with a portion to maintain a valve stem in a straight line transversely of the anvil while being swaged.

5. In a valve stem lengthener, the combination of a body having a stem channel 110

- therethrough and a transverse channel intersecting the same, an anvil disposed toward one end of the transverse channel and supporting the body reciprocably, a cooperating hammer element reciprocably disposed toward the other end of said transverse channel, and cooperating means for optionally varying the length of the stem channel.
6. In a valve stem lengthener, the combination of means for supporting the valve stem against lateral distortion, and opposed,

cooperating means for simultaneously swaging opposed portions of the valve stem.

7. In a valve stem lengthener, the combination of means for holding a valve stem against lateral distortion, means for swaging one side of the valve stem, opposed means for swaging the opposite side of the valve stem, and cooperating means disposed in line with the valve stem, for gaging the extent of the lengthening operation.

JOHN J. McGUCKIN.
